UNITED STATES PATENT OFFICE.

CHARLES W. GRUBE, OF PROVIDENCE, RHODE ISLAND.

DESIGN FOR A BADGE.

SPECIFICATION forming part of Design No. 23,922, dated January 1, 1895.

Application filed November 14, 1894. Serial No. 528,833. Term of patent 3½ years.

To all whom it may concern:

Be it known that I, CHARLES W. GRUBE, a citizen of the United States, residing at Providence, in the county of Providence, in the 5 State of Rhode Island, have invented and produced a new and original Design for a Badge, of which the following is a specification, reference being had to the accompanying drawing, which shows in front view the 10 badge and forms a part hereof.

The leading features of my design consist of a triple cross, upon which is displayed a Maltese cross, having a central medallion, all 15 which parts (except the upper and lower ends of the triple cross) are within the outer circumference of a circle, which circumference is also the exterior line of a circular band, having a shield-like expansion on the two sides thereof laterally, a panel, tangential to 20 said band at the top thereof, a curved ribbon-like bar, ornamented above by a helmet and below by crossed swords and centrally with three shields, said bar and panel being connected by links, as hereinafter particularly 25 described. Upon the outer circle is a triple cross, and upon said cross, between the upper and lower arms thereof, is a Maltese cross, and centrally upon the Maltese cross is a circular medallion, having a circular band. 30 The outer circle of the design is a circular

band, whose inner edge touches the corners of the Maltese cross. Upon said band at the extremities of the central cross bar of the triple cross, are oval shields, whose major axes are slightly larger than the width of said 35 central cross bar. A top panel surmounts said outer circle and has the scroll ornaments shown in the drawing. The bar is a curved ribbon-like piece, with notched flowing ends. In the center of said bar is a group of three 40 shields triangularly arranged. Crossed swords having cross-shaped hilts extend inwardly and upwardly, below and beneath the ribbon-bar and on the top of said ribbon-bar is a plumed and closed helmet. Rings and links 45 connect said bar and panel. The triple and Maltese crosses have a narrow band along their edges and the parts of the design have ornamental chasing as fully shown in the drawing. Upon said medallion, shields and 50 panels, or either of them, any suitable words, numerals, legends or emblems may be displayed.

I claim—

The design for a badge herein described and 55 shown.

CHARLES W. GRUBE.
